(57) **CLAIM**

The ornamental design for an electrical power unit for a work surface, as shown and described.

DESCRIPTION

FIG. 1 is a top perspective view of an electrical power unit for a work surface showing our new design;

FIG. 2 is a bottom perspective view thereof;

FIG. 3 is a top plan view thereof;

FIG. 4 is a bottom plan view thereof;

FIG. 5 is a rear elevation thereof;

FIG. 6 is a front elevation thereof;

FIG. 7 is a right side elevation thereof;

FIG. 8 is a left side elevation thereof;

FIG. 9 is a top perspective view of another electrical power unit for a work surface showing our new design;

FIG. 10 is a bottom perspective view thereof;

FIG. 11 is a top plan view thereof;

FIG. 12 is a bottom plan view thereof;

FIG. 13 is a rear elevation thereof;

FIG. 14 is a front elevation thereof;

FIG. 15 is a right side elevation thereof; and,

FIG. 16 is a left side elevation thereof.

In the drawings, the broken lines depict unclaimed subject matter only and form no part of the claimed design.
